(57) **CLAIM**

The ornamental design for a steering wheel cover, as shown and described.

DESCRIPTION

FIG. 1 is a front perspective view of the steering wheel cover showing my new design. The placement of a typical steering wheel is shown by dotted lines.

FIG. 2 is a rear perspective view thereof. The placement of a typical steering wheel is shown by dotted lines and is not part of the claimed design.

FIG. 3 is a left side elevational view thereof.

FIG. 4 is a right side elevational view thereof.

FIG. 5 is a top plan view thereof; and,

FIG. 6 is a bottom plan view thereof.
